Primary Examiner — Llorellys Martinez(74) *Attorney, Agent, or Firm* — Goldstein Law Offices, P.C.(57) **CLAIM**

The ornamental design for a diamond jewelry item, as shown and described.

DESCRIPTION

FIG. 1 is a perspective view of a diamond jewelry item showing our new design.

FIG. 2 is a top plan view thereof.

FIG. 3 is a bottom plan view thereof.

FIG. 4 is a front elevational view thereof.

FIG. 5 is a rear elevational view thereof.

FIG. 6 is a left side elevational view thereof; and,
FIG. 7 is a right side elevational view thereof.

The broken lines in the drawings represent portions of the diamond jewelry item that form no part of the claimed design.
